Attorney

UNITED STATES PATENT OFFICE.

DICK J. BAAS, OF PEASE, MINNESOTA.

AUTOMATIC IGNITION-CONTROL DEVICE FOR ENGINES.

Application filed June 1, 1925. Serial No. 34,155.

This invention relates to an improved device adapted for use in association with a water tank, and the purpose is to provide a means for automatically stopping a pump 5 operating engine by short circuiting the ignition circuit.

The principal object is to prevent water from overflowing a reservoir or tank by utilizing the water itself as a means for 10 bridging spaced contacts on a circuit closing device so that when the water reaches a predetermined level, it will bridge said contacts, close the circuits, and short circuit the ignition to the engine, whereby to stop the 15 engine and to prevent further pumping of water to the tank.

The invention is characterized by utmost simplicity of construction, the same simply embodying a circuit closing device mounted 20 on the tank in a position to be acted on by the water, together with conducting wires.

Other features and advantages of the invention will become apparent from the following description and drawing.

25 In the accompanying drawing forming a part of this application and in which like numerals are employed to designate like parts throughout the same:

Figure 1 is a side elevation, with portions 30 in section, showing the engine, pump, tank, and the improved short circuiting device.

Figure 2 is an enlarged detail sectional view of the circuit closer per se.

Referring to the drawing in detail, the 35 reference character 1 designates an ordinary internal combustion engine such as is used for operating a conventional form of water pump 2. The water is carried from the pump up through a pipe 3 and delivered 40 into a reserve tank 4 mounted upon an appropriate support 5. These details are conventional.

The invention comprises a circuit closer 6, and this is preferably of the construction 45 shown more plainly in Figure 2. Referring to Figure 2 it will be seen that the same comprises a cup 7 with an insulation filler, there being a contact or electrode 8 carried thereby. At the top is a binding post 9 with 50 which a current ground wire 10 is connected. Extending through the center of the cup is a tube 11 filled with insulation in which an electrode 12 is embedded. The current supply wire or cable 13 is connected with this 55 electrode. The ground wire is secured by

a clamp 14 upon the pump pipe 3, and the current is thereby carried down the pipe, and diverted through a ground wire 15 anchored upon the base of the engine. In this connection I might state that the ground 60 wire can simply be carried down and connected to a peg driven in the ground. The current conducting wire 13 is connected with a part 15 of the ignition system of the engine.

65 It is clear from the foregoing that after the engine has started and water has been elevated into the tank 4 by the pump 2, when the water level reaches a certain height in the tank, it will bridge the electrodes 8 and 12. It is clear that when this happens, the current ordinarily passing through the ignition system of the engine is shunted through this supplemental circuit provided, and is 70 grounded. Thus, the engine is stopped and 75 further pumping of water to the tank is prevented. Consequently, the water will not overflow from the tank.

An invention of this kind is characterized by exceeding simplicity, owing to the 80 fact that no floats or movable parts are employed, and there are no parts to get out of order. This is connected in parallel with the ignition circuit of the engine, and the engine ignition and invention operate independent of each other. The device may be 85 used to good advantage on stock farms for supply tanks in barns or tanks outside, in the pastures. It automatically regulates the level of the water in the tank, absolutely 90 prevents overflowing, and obviates the necessity of the farmer maintaining a watch over the pumping operation. The farmer can start the engine and then leave it and attend to his other work, and the level of the 95 water in the tank will be automatically controlled. The invention has been actually used, and has proved to be successful in 100 every phase. It is particularly useful in conjunction with high tension ignition used either on high tension magnetos, or jump 105 spark coil and battery systems. There is no regulation of distance between the engine and tank. These and other advantages and features of the invention have doubtless been made clear by the foregoing description and drawings and will be appreciated by those skilled in the art to which the invention relates. For this reason a more lengthy description is thought unnecessary.

Minor changes coming within the field of invention claimed may be resorted to if desired.

Having thus described the invention, what I claim as new and desire to secure by Letters Patent is:—

As an article of manufacture, a circuit controlling device, comprising a cup-shaped receptacle, a tubular member formed of insulating material mounted in and having one end extending through an opening in the bottom of said receptacle, and terminating in spaced relation below said bottom, a

filler of insulating material mounted in said tubular member, and an electrode secured in said tubular member by said filler and extending beyond the end of said member, a second electrode mounted on the side and projecting beyond the bottom of said cup-shaped receptacle, said electrode being in substantially spaced parallel relation, and terminal connections for each of said electrodes.

In testimony whereof I affix my signature.

DICK J. BAAS.
